(57) CLAIM

The ornamental design for a camping toilet seat, as shown and described.

DESCRIPTION

FIG. 1 is a perspective view of a camping toilet seat, illustrated with a stand and bag, showing the new design; FIG. 2 is a perspective view of the camping toilet seat, showing the new design;

FIG. 3 is a bottom perspective view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof; and,

FIG. 9 is a bottom plan view thereof.

The broken line showing of stand and bag in FIG. 1 and the bottom portion of the toilet seat in FIG. 8 is for the purpose of illustrating portions of the camping toilet seat that form no part of the claimed design.
